UNITED STATES PATENT OFFICE

101,442

DESIGN FOR A VALVE CONTROL UNIT

Henry Dreyfuss, New York, N. Y., assignor to
Crane Co., Chicago, Ill., a corporation of Illinois

Application May 15, 1936, Serial No. 62,659

Term of patent 14 years

To all whom it may concern:

Be it known that I, Henry Dreyfuss, a citizen of the United States, residing at New York, in the county of New York and State of New York, whose post-office address is 501 Madison Avenue, New York, New York, have invented a new, original, and ornamental Design for a Valve Control Unit, of which the following is a specification, reference being had to the accompanying drawing, forming part thereof.

Fig. 1 is a plan elevation of a valve control unit showing my new design.

Fig. 2 is a front view thereof.

Fig. 3 is a side view thereof.

I claim:

The ornamental design for a valve control unit, substantially as shown.

HENRY DREYFUSS.
